HAIR STRAIGHTENING DEVICE

Arthur L. Thomas, Trenton, and Lily D. Ellis,
Princeton, N. J.Original application September 23, 1933, Serial
No. 690,714. Divided and this application Sep-
tember 17, 1934, Serial No. 744,402

3 Claims. (Cl. 132—36)

This invention relates to a device for straightening kinky or wavy human hair.

The subject matter hereof is a division of our allowed application Serial No. 690,714, filed September 23, 1933.

An object of the invention is the provision of a device of the indicated character, whereby the straightening or altering of the structure of kinky or wavy hair may be effectually accomplished so that the hair will be straightened with a permanent effect.

Another object of the invention is the provision of a device of the indicated character whereby the method of straightening kinky or wavy hair described in the above-mentioned application may be effectually practiced.

The invention consists in a device characterized by the novel and improved features illustrated in the accompanying drawing and hereinbelow described and claimed.

In the drawing—

Figure 1 is a side view of a device embodying the features of the invention, the device being shown in use;

Fig. 2 is an enlarged longitudinal section of the device, portions thereof being broken away;

Fig. 3 is a section taken on the line 3—3 of Fig. 2, and

Fig. 4 is a view of one end portion of the flat bar or plate against which the hair is laid in the straightening operation.

The invention contemplates a device whose specific features are illustrated in the drawing by way of example. The device includes inner and outer tubular metal shells 10 and 11, respectively, each of which is substantially of oval formation with opposite sides practically flat. The inner shell 10 constitutes an oven and is longer than the outer shell 11. This outer shell 11 constitutes a cover for an electric heater 12, which is arranged in the space provided between the shells 10 and 11. The heater 12 may be of any suitable type, which has not been illustrated in detail but which consists of a shell

45 of mica, heat-resisting and electrical insulating cement in which the heating element is embedded, and an outer asbestos covering which will be disposed next to the outer shell 11. An extension cord 13 having the usual conductors supplies current to the heater 12. The ends of the outer shell 11 are closed by collars 14, which are slipped over the inner shell 10 and are fastened to the outer shell 11 in any suitable manner. These collars are made of a heat-resisting 50 and electrical insulating material. The exten-

sion cord 13 extends through one of the collars 14, as shown in Fig. 2. The device also includes a flat elongated plate or bar 15 of metal or any other suitable rigid material. The bar 15 is of a length to extend through the oven provided by the inner shell 10 and is of a cross-sectional size as to leave a space surrounding the same when disposed in the oven, which space will be occupied by the hair and other accessories to be hereinafter described. The bar 15 has a plurality of notches 16 in one end thereof to receive the cord or string for the purpose of fastening the hair to the bar.

It is to be understood that the hair will be properly treated according to known methods preparatory to being subjected to the influence of the device. A strand of the treated hair is laid on the bar 15 of the device and is secured at the scalp end by tying the same with a cord or tape extended in the notches in the end and sides of the bar 15, as shown. Next, an absorbent material is dipped in a solution containing an ingredient to cut the solution previously used on the hair and also ingredients to soften the hair. The absorbent material is then wrapped around the bar 15 and the hair laid against the same in straightened condition. Next, a heat-conducting material, such as metal foil, is wrapped around on the absorbent material in such manner so that approximately one-quarter inch extends beyond the bar at the scalp end thereof. A felt pad is then slipped over the wrappings on the bar and is brought in contact with the scalp to protect the same from the heat, and a protecting clip of heat-resisting material is clamped over the wrappings beyond the bar to prevent the heat from escaping to the scalp. The oven 10 and attached heater are placed over the wrapped hair, and the current is turned on. Heat will be applied removing all moisture and acting on the structure of the hair whereby it will be changed so that the hair will remain straightened with a permanent effect.

We claim:

1. A hair straightening device comprising a tubular oven, heating means surrounding said oven, and a flat bar adapted to extend through said oven, said bar having provision for securing the scalp ends of the hair thereto while the hair is laid lengthwise of the bar.

2. A hair straightening device comprising a tubular oven, heating means surrounding said oven, and a flat bar adapted to extend through said oven, said bar having notches in one end thereof to accommodate a tying element to se-

cure the scalp ends of the hair thereto while the hair is laid lengthwise of the bar.

3. A hair straightening device comprising an inner and an outer tubular shell, an electrical heating means arranged between said shells, the inner shell constituting an oven, and a flat bar

for the hair which may extend through said oven, said oven having a cross-sectional shape substantially similar to the cross-sectional shape of the bar.
